TWIN CYLINDER ENGINE

Charles Monti, Bay Shore, N. Y.

Application October 29, 1937, Serial No. 171,615

1 Claim. (Cl. 123—48)

This invention relates to new and useful improvements in a twin cylinder engine.

The invention has for an object the arrangement of the cylinders of an engine in a particular manner.

More specifically, it is contemplated to arrange them in pairs, the cylinders of each pair being radially distanced 180° from each other.

Still further the invention proposes to utilize a conventional crankshaft with a plurality of crank elements for connecting with the connecting rods of the pistons of the cylinders for the conventional operation.

Specifically, it is proposed to arrange the connecting rods of each pair of cylinders with different ones of said crank elements.

Still further the invention proposes the association of an eccentric bushing with each of the cranks in a particular manner so as to be capable of being adjusted for controlling the compression characteristics of the cylinders and other characteristics of the engine.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a transverse sectional view of a twin cylinder engine constructed according to this invention, with schematic ignition wiring applied thereto.

Fig. 2 is a transverse sectional view of the engine shown with a pair of the pistons in the suction position.

Fig. 3 is a view similar to Fig. 2 but showing the pistons in the compression position.

Fig. 4 is another view similar to Fig. 2, but illustrating the power stroke.

Fig. 5 is another view similar to Fig. 2 but illustrating the exhaust.

Fig. 6 is a sectional view similar to Fig. 2 but of a modified engine, vertical type.

Fig. 7 is a sectional view of another engine constructed according to this invention.

Fig. 8 is a fragmentary sectional view of a portion of the crank shaft and connecting rods of a modified form of invention.

Fig. 9 is a sectional view taken on the line 9—9 of Fig. 8.

The twin cylinder engine, according to this invention, is provided with a plurality of pairs of cylinders 10^a, 10^b, 11^a, 11^b, 12^a, 12^b, 13^a and 13^b.

The cylinders of each pair are arranged radially distanced 180° from each other. A crank shaft 14 is provided with a plurality of cranks 14^a. Connecting rods 15 connect together the pistons of each pair of the cylinders with different ones of the said crank elements 14^a.

The particular engine illustrated in Fig. 1 is an 8 cylinder engine, but this is merely for illustrative purposes as the invention may be applied to different numbers of cylinders.

In Fig. 1 a preferred wiring for the engine is disclosed. A distributor 16 is connected with a circuit 17 for controlling the ignition of cylinder 10^a and 12^b. A circuit 18 controls cylinder 12^a and 10^b. A circuit 19 controls cylinder 13^a and 15^b. A circuit 20 controls cylinder 11^a and 13^b.

Sectional view Fig. 2 illustrates a section through two of the cylinders which fire simultaneously. These cylinders are in the suction positions. In Fig. 3 the crank shaft is shown turned to a position in which compression is taking place. In Fig. 4 we have the explosion stroke, and in Fig. 5, the exhaust.

The engine illustrated in Figs. 1—5 inclusive is one in which the cylinders are arranged horizontally.

In Fig. 6 a modification of the invention is shown in which there is a vertical sectional view of an identical engine to that previously described, except positioned with the cylinders vertically. It should be understood that the invention is applicable to horizontal, vertical, and all different angularly positioned engines.

In Fig. 7 another embodiment of the invention has been disclosed which distinguishes from the prior form merely in the construction of the crank shaft. The crank shaft 14' is provided with a plurality of cranks 14^{aa} and between each of these cranks there is a bearing 22. It is in this respect that Fig. 7 distinguishes from Fig. 1 in which there is a bearing 23 between the pairs of the rungs of the crank shaft.

In Figs. 8 and 9 a modification of the engine has been disclosed wherein there is an arrangement for controlling the degree of compression of the engine. This controlling means is associated, particularly, with the crank shaft and the connecting rods. There is a crank shaft 14'' having crank elements 14^{aa}. Each of these crank elements is provided with an eccentric bushing 23. This eccentric bushing has an outer peripheral surface of true cylindrical form. The eccentricity is accomplished by the fact that the bore through which the crank element 14^{aa} passes is arranged off center. The eccentric bushing 23 is also pro-

vided with disc shaped end flanges 24 which are in face contact with the radial arm portions of the crank shaft. Set screws 25 threadedly engage through the radial arm portions and the 5 crank shaft and abut against the flange portions 24 for holding the eccentric bushing in rotative adjusted position; that is, fixed upon the crank element 14^{aa}.

The connecting rods of each pair of cylinders 10 are rotatively mounted adjacent each other on different ones of the eccentric bushings 23. On each bushing the connected rods are separated from each other by a washer 26.

The screw 25 may be loosened to free the eccentric bushing 23, which then may be turned on the crank element 14^{aa} for drawing in or extending the connecting rods mounted thereon. In this manner the compression of the cylinder 15 to which the connecting rods are associated may 20 be controlled. The compression compass may be increased or decreased. In this manner the characteristics of the engine may be varied and controlled.

The other details necessary to have an operative engine are not disclosed in this specification 25 since they are well known to those skilled in the art. Specific reference is had to a lubricating system, a cooling system, a valve system and all the other intricacies generally associated with an 30 engine of the type illustrated, are well known.

While I have illustrated and described the preferred embodiments of my invention, it is to be understood that I do not limit myself to the precise constructions herein disclosed and the right is reserved to all changes and modifications 5 coming within the scope of the invention as defined in the appended claim.

Having thus described my invention, what I claim as new, and desire to secure by United States Letters Patent is:—

In an engine, a cylinder, a piston slidably supported in said cylinder, a connecting rod connected at one end to said piston, a crank element connected to the other end of said rod for turning said element when said piston moves in said cylinder, and means on said crank element capable of being adjusted for controlling the path of movement of said piston within said cylinder, so that the compression limit of said piston may be increased or decreased, as desired, comprising 15 an eccentric bushing rotatively supported on said crank element and having the said end of said connecting rod rotatively supported thereon, and means for holding said bushing against rotating on said crank element for holding it in adjusted 20 positions, comprising outwardly extending flanges formed on the ends of said bushing, and set screws engaging through portions of said crank element and abutting said bushing.

CHARLES MONTI. 30
